UNITED STATES PATENT OFFICE.

DAVID J. TIMLIN, OF FLORISANT, MISSOURI.

SPARK-ARRESTER.

SPECIFICATION forming part of Letters Patent No. 234,349, dated November 9, 1880.

Application filed March 9, 1880. (No model.)

To all whom it may concern:

Be it known that I, DAVID J. TIMLIN, residing at Florisant, in the county of St. Louis and State of Missouri, have invented Improvements in Spark-Arresters, of which the following is a specification.

Figure 1 is an axial section. Fig. 2 is part in section and part in side view. Fig. 3 is a top view of the spark-deflector.

10 My improvement relates to a construction for the separation of the sparks from the smoke to prevent the escape of the former from the mouth of the stack.

A is the outer casing of the body or stem 15 B. C is the saddle, which is attached, as usual, to the locomotive. The body B extends up through the lower part of the flaring collar D in an extension, B'.

F is the deflector. This is of conical form 20 and ends at top in a goose-neck or curved pipe, G, which receives the sparks and conveys them downward to the annular cinder-chamber H between the body and the case. The pipe G may, if preferred, lead to some other 25 place—for instance, be continued downward and discharge the cinders upon the track, as indicated in dotted lines in Fig. 1.

The pipe G, instead of descending outside 30 the cap or casing K, may extend down between the deflector and the casing K. Where the cinders are delivered upon the ground or to other place than to the chamber H the case A may be dispensed with.

I is an orifice through the case A for the 35 discharge of cinders from the chamber H. This orifice may be closed by a slide, I', or otherwise. The orifice I may have a pipe conducting the cinders and sparks to the ground or any other place.

40 d d are orifices in the flaring collar D for the escape of smoke, &c., from the cinder-chamber H.

It will be seen that the lower end of the deflector F has greater diameter than the top 45 B' of the body, so that all the heavier parts of the products of combustion are projected into the deflector, where they are concentrated to the discharge-orifice f and pass into the pipe G. The deflector has in its sides orifices f' 50 for the lateral escape of smoke and gases. The

orifices are inclined downwardly toward the outer ends, so that the cinders will not be carried through them by the force of the blast.

It will be seen that as the cinders have a rapid upward motion, and are heavy as compared 55 with the smoke, they will pass upward to the discharge f, while the smoke will be crowded outward by the contracting form of the deflector, and having but little momentum will escape laterally through the downwardly-inclined orifices f'. The smoke, having little 60 specific gravity, will some of it escape laterally before reaching the deflector, and will pass upward through the orifices f² in the flange F' of the deflector, and will have free 65 egress through the mouth or upper end, J, of the casing or open cap K. The course of the smoke is shown by single-headed arrows and that of the cinders by double-headed arrows.

I claim as my invention—

70

1. In a spark-arrester, the conical deflector F, with openings f, f', and f², substantially as shown and described.

2. The combination of upright open-bottomed conical deflector having an opening, f, 75 at the apex and side openings, f', and the conducting-pipe G, substantially as set forth.

3. The body B, with extension B' and flaring collar D, in combination with the deflector, when the parts are constructed and relatively 80 arranged substantially as set forth.

4. The combination of body B, conical deflector having its face downward, and with side openings for escape of smoke, and pipe leading from the apex of the deflector to the 85 cinder-chamber H, or otherwise.

5. The conical deflector F, when provided with orifice f and with inclined orifices f', in combination with conducting-pipe G, for the purpose set forth.

90

6. In a spark-arrester, the deflector F in the form of an upright cone, having orifice f at the apex and side orifices, f', downwardly inclined from the interior, as and for the purpose set forth.

DAVID J. TIMLIN.
